C. W. VOLLMAN

COMPRESSOR

Filed Feb. 15, 1922

UNITED STATES PATENT OFFICE.

CARL W. VOLLMANN, OF MONTREAL, QUEBEC, CANADA.

COMPRESSOR.

Application filed February 15, 1922. Serial No. 536,626.

This invention relates to ammonia compressors and compressors for compressing air, carbonic acid gas or any other gaseous fluid requiring compression for manufacturing purposes; while the invention relates more particularly to the type of compressor in which flat steel springs are employed as valvular members.

The object of the invention is to increase the durability of the valves, ensure more efficient working thereof and increase the capacity of the valve and secure more perfect valvular action.

More specifically stated the invention consists of the construction, combination and particular arrangement of the parts of the suction and discharge valves of a compressor of the type defined, as described hereinafter.

For full comprehension, however, of my invention reference must be had to the accompanying drawings in which similar reference characters indicate the same parts and wherein:

Figure 1 is an axial sectional view of my improved suction valve with the valvular members indicated in their open position;

Figure 2 is a fragmentary view of the right half of the valve with the valvular members closed;

Figure 3 is a transverse sectional view taken on line 3—3 Figure 1;

Figure 4 is a transverse sectional view taken on line 4—4 Figure 1;

Figure 5 is an axial sectional view of the discharge valve;

Figure 6 is a fragmentary view showing the right half of the discharge valve with the valvular members closed;

Figure 7 is a transverse sectional view taken on line 7—7 Figure 5;

Figure 8 is an axial sectional view taken on line 8—8 Figure 5; and

Figure 9 is an elevation of a front cylinder cover provided with my improved valves.

The suction valve according to my invention consists of a hollow cylindrical intake member *b*, one end of which is closed by a cap *c* and the opposite end *d* of which is tapered to present a hollow member of substantially truncated conical form with a closed end *e*, the interior of the member forming an intake chamber *b*¹. This intake member is

mounted in position upon a valve case *g* with the truncated conical portion extending into the latter, the exterior of the member having a shoulder *f* constituting a seat adapted to engage the adjacent end of the valve case. The opposite end of the valve case is as usual with valves of this nature inwardly converged as at *h* to be seated in the housings or seats *k* of the cylinder cover of the compressor. The truncated conical member *d* has a series of elongated ports in the form of slots *m* extending from its closed end to within a short distance of the point where the conical portion merges into the cylindrical portion. These ports *m* are adapted to effect communication between the intake chamber *b*¹ and the valve chamber *g*¹ and are controlled by an equal number of resilient check valves *p* clamped in place by blocks *o*. These blocks are accommodated by an inwardly offset portion *n* of the intake member. The space provided by this inwardly offset portion is such that the surrounding face of the valve case *g* fits tightly over the blocks *o* and supplements the blocks in their clamping action, thus preventing displacement of the check valve even if their fastening means become loose. These blocks vary in number according to the size of the compressor, the size illustrated having eight ports and the cone, consequently for convenience, having an octagonal exterior in cross section, each facet or side thus produced serving as an external valve seat *t*. Each of the blocks *o* secures one of the check valves in place. The latter are equal in number to the number of ports and each consists of a flat steel spring of slightly greater width than its port and of sufficient length to completely overlie the full length of the port. Each spring has one end bent at slightly greater than a right angle and fitted between one side of its block *o* and the portion *n* and the face of the cone. These blocks are held in place by screws *q* located one at each side of the springs and having their heads countersunk in the blocks. This manner of clamping the springs avoids making holes therein or in any way weakening them. In order to prevent the valvular springs from being unduly sprung when thrown open by the sucked fluid a series of beds *s* are cast upon or otherwise fastened

to the interior of the valve chamber in juxtaposition with the springs and presenting faces conforming to the contour assumed by the spring when bent to open position.

5 My improved discharge valve consists of a combined cylindrical discharge member and valve chamber or case *t*, the lower end of which is seated upon a circular base *u*, the configuration of the latter being converged 10 as at *v* to fit the usual seat on the cylindrical cover. The base has a hollow tapered member *w* of substantially wedge form slotted to provide elongated ports *x*. Check valves in the form of flat steel spring val- 15 vular members *y*, similar to the valvular members *p*, are clamped to this base near one end of the slots by clamping bars *z*. These clamping bars are accommodated between the foot 2 of the cylindrical member *t* and 20 the outer face of the wedge member. This hollow-wedge-like member *w* is slightly less in length than the diameter of the housing *k*, and projects from the base *u* a sufficient distance to locate the contiguous ends of the 25 ports *x* in close communication with a discharge port 12. Seats for supporting the valvular springs when thrown open in the discharge valve are indicated at 9.

The intake port is indicated at 10 in Figure 1 and the discharge port at 12 in Figure 5. Communication is effected between the intake member *b* and the intake port 10 through an aperture 15 in the side of cylindrical member *b*, and communication is effected between the valve chamber *t* and discharge port 12 by an outlet opening 16.

In order to increase the effective closing of the valves the clamping blocks *o* and bars *z* have the springs countersunk therein to 40 slightly less than the full thickness of such springs. This countersinking also acts to prevent displacement of the springs from their proper engaging position relatively to the ports.

45 The flat top of the wedge-like member *w* has a screw-threaded hole 20 to permit a bolt to be screwed into it for the purpose of lifting the valves from its case.

The hollow tapered members *d* and *w* with their elongated ports impart to the valves the advantage of having maximum capacity for the flow within valves of given dimensions.

The outlet valve is not claimed herein specifically as the same forms the subject-matter of a separate application.

Operation.

60 During the operation of a compressor provided with my improved valves the force of suction throws open the valvular springs to the position shown in Figure 1 and the flow of the fluid opens the valves by bending them away from the ports and as they 65 are attached at the ends of the ports nearer

the large intake port 10 these valvular springs in opening are presented and supported substantially parallel to the line of flow as shown by the arrows in this Figure thus offering minimum resistance. The valvular members *y* of the discharge valve are also thrown open to positions substantially parallel to the line of flow and offer minimum resistance, the supports 9 preventing these valvular members from being unduly sprung.

These supports for the valvular springs and the manner of attaching the springs with their attached ends upon the clamp their clamping devices, increase the durability of the valves and ensure the more efficient working thereof, while the particular arrangement of these valves acting upon the outside of the conical member *d* and the outside of the wedge member *w* permits the valve seats to be readily machined and a perfectly tight joint to be secured between each valvular spring and its seats, thus, with the particular arrangement of the valve mounting, securing maximum efficiency in operation. Another important advantage is that the direct inward and outward flow from the suction port 10 to the ports *m* and the ports *x* to the discharge port 12 affords relatively greater capacity than can be secured without the use of the hollow truncated conical member *d* and wedge *w* or their equivalents.

Although I have illustrated and described the preferred embodiment of my invention many changes may be made in specific detail design and particular arrangement of devices and the relative dimensions thereof without departing from the spirit of my invention.

What I claim is as follows:

1. In a compressor for gaseous fluid, an intake member of circular cross-section at its upper portion and having an intake opening in its side and its top permanently closed, the member being reduced in diameter at its lower portion forming a shoulder, the lower portion consisting of a hollow member of truncated conical form and closed at its truncated lower end and having a surrounding series of longitudinal ports radially opening, a valve case equal in diameter to the upper portion of the intake member and seated against the shoulder and enclosing the truncated conical member, a plurality of separate and distinct check valves equal in number to the number of the openings and of uniform width throughout their length and controlling the ports, each valve independently controlling only one of the ports, and means for securing the valves at the ends of the ports from which the flow passes therethrough and permitting them to open in the direction of the flow.

2. An intake member for a gas com-

pressor, such as claimed in claim 1, the means for securing the valves whereof in place consisting of the truncated conical member being constructed and arranged to form an encircling space within the valve case, a circumferential series of segmental blocks within the space and clamping the

valves in place, means for fastening the blocks and the valve case locking fastening means and clamping blocks against displacement. 10

In testimony whereof I have signed my name to this specification.

CARL W. VOLLMANN.
